[57] CLAIM

The ornamental design for a directory stand, as shown
and described.

DESCRIPTION

FIG. 1 is a front elevational view of a directory stand
showing our new design;

FIG. 2 is a left side elevational view, the right side being
a mirror image;

FIG. 3 is a rear elevational view; and,

FIG. 4 is an enlarged sectional view along line 4—4 of
FIG. 2.

*FIG. 1**FIG. 2**FIG. 3*

FIG. 4
